U.S. Cl. 424—184

2 Claims

ABSTRACT OF THE DISCLOSURE

A method for altering the reproductive function of mammals by administering a pharmacologically effective amount of certain organosilicon compounds. As a means of illustration, one can orally or parenterally administer from 1.0 mg. to 5000 mg. per kilogram of body weight (either as a single dose or as a daily dosage over a period of time) of an organosilicon compound of the formula

thereby rendering the subject (either a male or female mammal) infertile.

This application is a continuation-in-part of U.S. application, Ser. No. 741,336, filed July 1, 1968, now abandoned.

This invention relates to a method for altering the reproductive function of mammals.

We have discovered that the administration of a pharmacologically effective amount of certain organosilicon compounds can alter the reproductive function of mammals. More precisely, a male mammal so treated exhibits androgen depressant effects. For example, the sex accessory organs of the male (seminal vesicle, prostate) can be reduced in function and/or size and with sufficient dosage, the male can also be rendered infertile as a result of depression of testes size and function. A female mammal so treated exhibits an alteration of fertility, i.e., the female mammal's capability to conceive is inhibited such that the female may be rendered infertile or abort if pregnant.

The principal object of this invention is to provide therapeutically effective organosilicon compounds which can render a male or female mammal infertile. Another principal object of this invention is to provide a method of administering certain organosilicon compounds which can be useful in the treatment of prostatic hypertrophy by depressing androgen function in males. It is still another object of this invention to provide a method of administering certain organosilicon compounds to females whereby the female's capability to conceive or support and carry a living fetus through a normal pregnancy to a healthy birth can be inhibited. These and other attendant objects will become more readily apparent from the detailed description which follows.

This invention relates to a method for altering the reproductive function of mammals which comprises admin-

2

istering from 1.0 mg. to 5000 mg./kg. of certain organosilicon compounds to a mammal, said certain organosilicon compounds being selected from the group consisting of

55 (11) Siloxanes having three silicon atoms per molecule said silicon atoms being linked by divalent oxygen atoms, at least one of the silicon atoms having one valence being satisfied by a substituent selected from the group consisting of a phenyl radical and a hydrogen atom, the remaining valences of the silicon atoms being satisfied by substituents selected from the group consisting of phenyl radicals, hydrogen atoms, alkyl radicals having from 1 to 6 carbon atoms inclusive, and hydroxyl radicals, there being no more than two hydroxyl radicals or silicon-bonded hydrogen atoms per molecule and there being no more than 60 four phenyl radicals per molecule, and

(12) An equilibrated copolymer mixture consisting primarily of about 60 weight percent of phenylmethyl-siloxane units and about 40 weight percent of dimethyl-siloxane units, said copolymer mixture being characterized by having a viscosity of 18.6 cs. to 21.7 cs. at 25° C., a specific gravity of 1.061 to 1.069 at 25° C., a refractive index of 1.4871 to 1.4929 at 25° C., an open cup flash point of 275° F. to 370° F., and an acid No. of trace to 0.0028 mg. of KOH per g. of sample.

Illustrative of the siloxanes (11) which are operable herein are the following:

(1)

(2)

(3)

(4)

(5)

(6)

(7)

(8)

(9)

(10)

The certain organosilicon compounds noted herein can be readily prepared by well known techniques described

in the literature, e.g., by the cohydrolysis of chlorosilanes or by a suitable Grignard reaction.

The process of the present invention is operative on any mammal, e.g., rodents such as mice, rabbits and rats; domestic animals such as cats, swine, dogs, cattle, horses, and sheep; animals wild in nature such as deer, fox, wolves and lynx; and primates such as monkeys and man.

One can administer the certain organosilicon compounds in any pharmacologically acceptable manner. They can be orally administered, parenterally administered or, in certain species, topically administered. The parenteral mode of administration would, of course, include subcutaneous administration, intramuscular administration and the like.

It is of importance to note that the organosilicon compounds described herein can be administered either in pure form in or combination with a pharmaceutically acceptable carrier or diluent. Suitable carriers include sesame oil, corn oil, mineral oil and other well known fat soluble carriers commonly employed in numerous pharmaceutical preparations.

As mentioned herein, the dose range of the organosilicon compound is in a pharmacologically effective amount. A dose range of from about 1.0 mg. to about 5000 mg. per kilogram of body weight has been found to be suitable; however, the precise dosage is ultimately dependent upon the particular compound and its isomers, the mammal used, the vehicle used, the route of administration, and the specific effects one wishes to achieve. The organosilicon compound may be administered as a single dose or it may be administered in daily dosage over varying periods of time, e.g., from about 7 to about 30 days or more.

The time required to achieve the desired effect is also variable, ranging anywhere from days to weeks or months, depending upon various factors, e.g., the species of mammal, dosage, route of administration, and the desired effect one wishes to achieve.

The particular alteration of androgen functions which have been observed after administering the compounds of the present invention to male mammals are a decrease in sex accessory organ function (decreased seminal fluid) and size (decreased seminal vesicle) and a decrease in prostatic or testicular function (decreased sperm count) or size.

In view of the above, the method of this invention can be useful for decreasing the size of male sex accessory organs. In this regard, sex accessory organs are more sensitive than the testes to these certain organosilicon compounds so that it is possible to decrease prostatic function and size without producing a significant effect on testicular size.

Furthermore, the method of this invention can be particularly useful for the treatment of prostatic hypertrophy. For example, by orally administering a compound of the formula

at a daily (seven daily doses) dosage level of 100 mg. per kg. of body weight, it has been found that the prostate is significantly reduced in size.

If a high dosage level is maintained over a fairly long period of time in females prior to, during and/or following copulation, the anticipated embryo may fail to form or it may be resorbed by the female mammal.

It is also possible to prevent pregnancy (contraception) or abort pregnancy in female mammals because of an estrogenic activity of certain of the organosilicon compounds described herein.

In all of the foregoing cases, the pharmacological actions are reversible.

The following examples are illustrative only and should not be construed as limiting the invention which is properly delineated in the appended claims.

EXAMPLE 1

This example illustrates androgen-depressant activity of a certain organosilicon compound in the male rat.

A group of male rats (Sprague-Dawley strain) were orally dosed via gastric intubation with an organosilicon compound of the formula

The animals were administered 100 mg./kg. of body weight of the compound for a period of seven days with autopsy on day eight. Final body weights were determined in the fasted state just prior to sacrifice. Table I illustrates the androgen-depressant activity noted above.

TABLE I

[Androgen-depressant activity of a certain organosilicon compound in the male rat]

Group	n	Mean initial body weight (grams)	Mean final body weight (grams)	Mean seminal fluid ratio, $\pm S.E.$	Mean seminal vesicle ratio, $\pm S.E.$	Mean prostate ratio, $\pm S.E.$	Mean testes ratio, $\pm S.E.$
Control (sesame oil)	10	380	384	.00264 $\pm .00020$	.00158 $\pm .00005$	.00119 $\pm .00005$	.00905 $\pm .00016$
$(\text{CH}_3)_2\text{Si}-\text{O}-\text{Si}-\text{C}_6\text{H}_5$	10	381	371	.00115 $\pm .00016$	.00100 $\pm .00005$	.00077 $\pm .00006$	.00860 $\pm .00018$

¹ Ratio equals organ or fluid weight (grams)/final body weight (grams).

² p <.001 compared to control.

*Daily oral dosing of 100 mg./kg. of body weight for 7 days with autopsy on day 8.

EXAMPLE 2

This example illustrates the structure-activity-relationship between rat androgen-depressant activity and certain organosilicon compounds.

A group of male rats and mice (Sprague-Dawley strain) were orally dosed with the organosilicon compounds heretofore defined which were diluted in sesame oil. Oral administration was achieved via gastric intubation. The period of dosage ranged from one to seven days at dose levels of 1, 10, 33, 50, 100, 1670, and 5000 mg./kg. of body weight. Final body weights were determined in the fasted state just prior to sacrifice. Sacrifice was carried out on day four, five, six, seven or eight depending upon the particular dosage regimen. Various organ weights were determined and ratios of the organ weights (grams) to final body weight (grams) were determined for comparison in both control and treated animals.

Table II (A through D) indicates the structure-activity-relationship referred to above with respect to dosage range for effect.

These dosages represent threshold doses for depression of seminal fluid, seminal vesicle, and/or testes weight ratios.

*Compound administered orally for three days with autopsy on day 4. Estradiol benzoate given subcutaneously in groups B, C and D.

EXAMPLE 6

This example illustrates the antifertility activity of a certain organosilicon compound administered orally for seven days prior to mating to proven breeder female mice.

A group of untreated female mice (Cox strain) were mated with a group of untreated male mice and animals which became pregnant and delivered an average normal litter in this first mating were then selected as proven breeders for a second mating. These mice in the second mating were orally dosed (via gastric intubation) with either nothing, sesame oil, or two different doses (50 mg./kg. of body weight or 200 mg./kg. of body weight) of an organosilicon compound of the formula

Table VI illustrates the antifertility activity noted above.

TABLE VI

[Antifertility activity of a certain organosilicon compound administered orally for seven days prior to mating to proven breeder female mice]

		First mating		Second mating	
		Number pregnant/total number	Mean number pups/female	Number pregnant/total number	Mean number pups/female
(A)	Control (no treatment)	3/3	9.33	3/3	13.0
(B)	Sesame oil	3/3	10.33	3/3	12.0
(C)	$\begin{array}{c} (\text{CH}_3)_2-\text{Si}-\text{O}-\text{Si}(\text{CH}_3)_2 \\ \quad \\ \text{O} \quad \text{O} \\ \quad \\ (\text{CH}_3)_2-\text{Si}-\text{O}-\text{Si}-\text{C}_6\text{H}_5 \\ \\ \text{CH}_3 \end{array}$ (50 mg./kg.)	3/3	10.33	1/3	14.0
(D)	$\begin{array}{c} (\text{CH}_3)_2-\text{Si}-\text{O}-\text{Si}-(\text{CH}_3)_2 \\ \quad \\ \text{O} \quad \text{O} \\ \quad \\ (\text{CH}_3)_2-\text{Si}-\text{O}-\text{Si}-\text{C}_6\text{H}_5 \\ \\ \text{CH}_3 \end{array}$ (200 mg./kg.)	3/3	10.67	1/3	18.0

EXAMPLE 7

This example illustrates the abortifacient activity of mixed low molecular weight cyclic methylphenylpolysiloxanes administered dermally from the sixth to the sixteenth day following mating in rabbits.

The mixed low molecular weight cyclic methylphenylpolysiloxane is a commercially available silicone equilibration product. For purposes of ease, it will be hereafter referred to as Organosilicon Compound A. It is made by a continuous process technique in commercial, steel equipment as follows:

To a copolymer mixture B* of phenylmethylsiloxane and dimethylsiloxane obtained from the sources indicated below, there was added a sufficient amount of a water-washed, 50 weight percent toluene solution C of a hydrolyzate of phenylmethyl dichlorosilane, and a sufficient amount of dimethylpolysiloxane D in the form of cyclics and hydroxyl-endblocked polymers having generally from about 3 to 10 siloxane units to yield a mixture containing about 6 parts by weight of phenylmethylsiloxane for every 4 parts by weight of dimethylsiloxane. To this mixture there was added sufficient toluene to make a solution containing about 35 weight percent of organopolysiloxanes.

This mixture of B, C and D is referred to below as (1). Where it is stated below that a given material is returned to (1), it is meant that it is placed in the initial reaction chamber as an ingredient for the next production run of product. Correspondingly, the present production run received similar ingredients from the production run which preceded it, the present material being made in a continuous process.

To (1) there was added a sufficient amount of a 45 weight percent solution of potassium hydroxide in water to provide about 0.5 mg. of potassium for every gram of organopolysiloxane present, and the mixture was heated with slowly increasing temperature up to the reflux temperature. The heating was performed under azeotropic conditions.

After about 20 hours of heating at the reflux temperature, the product was found to be an equilibrated phenylmethylsiloxane-dimethylsiloxane copolymer.

The equilibrated mixture was drawn off and neutralized to a slightly acid condition (acid number of about 0.02) by the addition of dimethyl dichlorosilane. This product was then filtered to remove solids and stripped at at-

mospheric pressure to about 115° C. The distillate B₁ which was primarily toluene, was recycled back to (1) while the residue was further stripped at about 30 mm. of pressure to a pot temperature of 200° C. (about 90° C. at the top of the distillation column).

The resulting distillate B₂ was returned to (1) while the residue was distilled at a pressure of about 2.5 mm. and a pot temperature of 300° C. (about 180° to 190° C. at the top of the distillation column).

The residue B₃ of this latter distillation was returned as needed to (1). (Occasionally, this residue was discarded if it appeared to contain an excess of impurities.) The distillate was stripped to about 100° C. at a pressure of about 2 mm.

The volatile fraction B₄ of this final distillation was returned to (1) while the residue is the product tested below, known as Organosilicon Compound A.

Thirty mature doe rabbits (Dutch Belted strain) were divided into three groups of ten each. One group served as a treated control (distilled water) whereas the Organosilicon Compound A was administered dermally (test material applied to the shaven back) at dose levels of 50 mg./kg. of body weight and 500 mg./kg. of body weight to the other two test groups respectively. Ten untreated proven bucks were used for breeding and each buck was mated to one doe in each of the three groups. Sufficient females were mated to obtain ten pregnant animals per group.

The abortifacient effect (number of young dead and alive) is presented in Table VII.

TABLE VII

[Abortifacient activity of mixed low molecular weight cyclic methylphenylpolysiloxanes administered dermally from the sixth to the sixteenth day following mating in rabbits]

Group	Number of implantation sites	Number of resorption sites	Number of normal young	
			Alive	Dead
Control (sesame oil)	65	0	64	1
Organosilicon Compound A (50 mg./kg.)	70	6	64	0
Organosilicon Compound A (500 mg./kg.)	42	42	0	0

EXAMPLE 8

This example illustrates antifertility in the male *Macaca mulatta* monkey.

A group of male *Macaca mulatta* monkeys were orally dosed with the Organosilicon Compound A of Example 8. Oral administration was achieved via gastric intubation. Dosage was for 90 days at a level of 50 mg./kg. of body

*B is composed of distillates B₁, B₂ and B₄ and residue B₃ which are shown below. These fractions are returned to (1) at different times.

weight or 2000 mg./kg. of body weight daily. After 90 days, an attempt to obtain seminal fluid was made and biopsies were conducted. The results are tabulated in Table VIII.

TABLE VIII

[Antifertility activity of mixed low molecular weight cyclic methyl-phenylpolysiloxanes administered orally for ninety days in the male Macaca Mulatta monkey]

Group	n	Results
Control.....	3	No alteration of seminal ejaculate, testicular size, or spermatogenesis as determined by biopsy after 90 days of dosing.
Organosilicon Compound A (50 mg./kg., daily dose).	3	{2/3 provided seminal ejaculate. 2/3 showed no alteration of testicular size. 2/3 showed no spermatogenic depression.
Organosilicon Compound A (2,000 mg./kg., daily dose).	3	{3/3 no seminal ejaculate obtained. 3/3 animals revealed atrophy of testes. 3/3 animals revealed spermatogenic depression.

That which is claimed is:

1. A method for decreasing the reproductive function of mammals comprising administering to a mammal an effective amount in the range of from 1.0 mg. to 10 mg./kg. of mammal body weight of 2,6-cis-diphenylhexamethylcyclotetrasiloxane.

2. The method of claim 1 wherein the decrease in reproductive function is a reduction in fertility of said mammal.
